UNITED STATES PATENT OFFICE.

CLIFFORD A. BARDEN, OF WAKEMAN, OHIO.

DESIGN FOR A CHILD'S RIDING-CAR.

55,234.

Specification for Design.

Patented May 25, 1920.

Application filed June 30, 1919. Serial No. 307,856. Term of patent 7 years.

To all whom it may concern:

Be it known that I, CLIFFORD A. BARDEN, citizen of the United States, residing at Wakeman, in the county of Huron and State of Ohio, have invented a new, original, and ornamental Design for a Child's Riding-Car, of which the following is a specification, reference being had to the accompanying drawing, forming part thereof.

The figure is a perspective view of a child's riding car, showing my new design.

I claim:

The ornamental design for a child's riding car, as shown.

Signed at Wakeman, Ohio, June 25, 1919.

CLIFFORD A. BARDEN.
